(57) **CLAIM**

We claim the ornamental design for a retractable cellular fabric with right angle triangular cells having arcuate vanes, as shown and described.

DESCRIPTION

FIG. 1 is a front isometric of the retractable cellular fabric with right angle triangular cells having arcuate vanes shown in an open condition.

FIG. 2 is an enlarged fragmentary front isometric view of the fabric shown in FIG. 1.

FIG. 3 is a left side elevation of the fabric as seen in FIG. 2 with the right side elevation being a mirror image.

FIG. 4 is a front elevation of the fabric shown in FIG. 2.

FIG. 5 is a top plan view of the fabric shown in FIG. 2.

FIG. 6 is a rear elevation of the fabric shown in FIG. 2.

FIG. 7 is a bottom plan view of the fabric shown in FIG. 2.

FIG. 8 is a front isometric of the fabric shown in FIG. 2 in a closed condition.

FIG. 9 is a left side elevation of the fabric as shown in FIG. 8 with the right side elevation being a mirror image.

FIG. 10 is a front elevation of the fabric as shown in FIG. 8.

FIG. 11 is a rear elevation of the fabric as shown in FIG. 8.

FIG. 12 is a top plan view of the fabric as shown in FIG. 8; and,

FIG. 13 is a bottom plan view of the fabric as shown in FIG. 8.
